(74) Attorney, Agent, or Firm — Banner & Witcoff, Ltd.

(57) CLAIM

The ornamental design for a shoe, as shown and described.

DESCRIPTION

The FIGURE is a photographic bottom view of a shoe showing my new design.

The lighter grey portions are for environmental purposes only and form no part of the claimed design. The broken lines immediately adjacent to the dark grey photographic area represent the bounds of the claimed design and form no part thereof.

1 Claim, 1 Drawing Sheet(56)
